H. TECHEL

UNDERWATER TORPEDO TUBE

Filed April 5, 1924

UNITED STATES PATENT OFFICE.

HANS TECHEL, OF KIEL, GERMANY, ASSIGNOR TO FRIED. KRUPP AKTIENGESELLSCHAFT GERMANIAWERFT, OF KIEL-GAARDEN, GERMANY.

UNDERWATER-TORPEDO TUBE.

Application filed April 5, 1924. Serial No. 704,402.

To all whom it may concern:

Be it known that I, HANS TECHEL, residing at Kiel, Germany, a citizen of the German Republic, have invented a certain new and useful Improvement in Underwater-Torpedo Tubes, of which the following is a specification.

This invention relates to under-water torpedo tubes.

With the under-water torpedo tubes used hitherto, the inner space of the launching tube is before the launching entirely filled by the torpedo and the surrounding water. During the launching the compressed ejecting air is introduced into the rear end of the tube, it presses on the water, the pressure transmits to the torpedo and causes its movement. As soon as the torpedo has left the tube, the air expands suddenly and rises upwardly in a large bubble producing at the water surface an undulating motion which is visible and audible to a large distance.

The invention has for its object to prevent the said undulating motion, this object being attained by arranging in the tube in rear of but not in contact with the torpedo a freely movable piston the rear face of which is acted upon by the driving medium.

The accompanying drawing illustrates, by way of example, a sectional view of an embodiment of the subject-matter of the invention.

The tube A is tightly closable at both ends by doors B and C as usual. The supply pipe D for the compressed air which is provided with a cock E, opens into the door B. The tube contains the torpedo F and a piston G arranged in rear of and at a certain distance x from the torpedo and bearing against an annular rubber buffer b^2 of the door B. Mounted on the rear portion of the tube A is an exhaust valve H for the compressed air which opens into the interior of the boat through an open branch J. The valve H is connected by means of a rigging K, L with a double-armed lever M mounted in a hollow bearing block N of the tube A. The lever M carries at its lower free end a pawl-like member O which is adapted to project into the path of the piston G after the torpedo has passed it, but which is prevented by a stop m^1 from swinging beyond a certain position. A pipe P closable by a cock Q establishes com-

munication between the tube A and a water tank R the capacity of which is equal to the space of the tube A not filled by the torpedo.

In describing now the operation of the invention it is assumed that the several parts are in the state illustrated in the drawing. The tube A is loaded with a torpedo F, the piston G is in the tube and the doors B and C are closed. Shortly before the launching, the cock Q is opened and the tube A filled with surrounding water from the tank R and then the door C is opened. For the purpose of launching, the cock E is turned into its open position, thereby permitting the admission behind the piston G of the compressed air designed to eject the torpedo. The air pressure drives the piston G forward and the latter transmits its motion to the surrounding water and the torpedo F. When sufficient compressed air has entered, the cock E is again closed.

As soon as the torpedo has glided past the lever M, the pawl O will drop by its own weight and abut against the stop m^1 . The piston G on its further course will strike against the pawl O and reverse the lever M. This movement is transmitted by the rigging L, K to the valve H opening the same, so that the compressed air contained in the tube in rear of the piston will exhaust into the interior of the boat. At the same time the piston comes to a standstill. As soon as the pressure of the air in the tube A has become smaller than that of the sea-water, the piston will be driven back by the external water pressure and caused to return into its initial position.

For the purpose of re-loading, in a well-known manner the tube is closed again and its water emptied into the tank R and another tank (not shown) arranged below the tube and having the volume of the torpedo. After opening the door B the piston G may be taken out and another torpedo introduced. Thereupon the piston G is re-inserted and the door B closed so that the tube is again ready for firing.

It is attained by the invention that the compressed air used for launching the torpedoes does not come into touch with the water and therefore produce no undulating motion which might betray the presence of a torpedo. As the driving piston is arranged at a certain distance behind the tor-

pedo, no danger exists of the piston injuring the steering means of the torpedo or its propeller shaft. Therefore, ordinary torpedoes may be used without any special protecting measures.

If the torpedo does not fit quite close in the tube, water will flow along the torpedo during the launching and the piston will approach the torpedo. In order to prevent 10 a contact of the piston and torpedo it is therefore necessary that the distance between them is sufficiently large from the beginning.

Claims:

15. 1. In an under-water torpedo tube, a freely movable piston for ejecting the torpedo, said piston being arranged in the tube in rear of but not in contact with the torpedo, and means for admitting compressed air to the rear side of the piston for the expulsion of the torpedo; a valve for allowing the exhaust of the air contained in the tube behind the piston after the expulsion, a lever pivotally supported by the tube and adapted to project into the path of the piston and to be reversed by the same and a 20 rigging connecting the lever with the said exhaust valve.
2. In an under-water torpedo tube, a freely movable piston for ejecting the torpedo, said piston being arranged in the tube in rear of but not in contact with the tor-
3. In an under-water torpedo tube, a freely movable piston for ejecting the torpedo, said piston being arranged in the tube in rear of but not in contact with the torpedo, and means for admitting compressed air to the rear side of the piston for the expulsion of the torpedo; turned into its initial position by the external water pressure.

HANS TECHEL.
